URINAL UNIT FOR INCONTINENT FEMALES

Edward J. Hill, 1660 Lochridge, Bloomfield Hills, Mich.

Filed Feb. 12, 1963, Ser. No. 73,516

Term of patent 14 years

(Cl. D83—1)

FIG. 1 is a side elevational view of a urinal unit for incontinent females embodying my new design;

FIG. 2 is a front elevational view;

FIG. 3 is a top view;

FIG. 4 is a bottom view; and

FIG. 5 is a rear elevational view.

I claim:

The ornamental design of a urinal unit for incontinent females, substantially as shown.
